UNITED STATES PATENT OFFICE

2,375,471

COMBINED GENERATOR AND LIGHTER FOR
OIL HEATERS

John S. Hodges, Riverside, Calif.

Application December 24, 1942, Serial No. 470,020

5 Claims. (Cl. 158—91)

This invention relates to a combined generator and lighter for oil heaters, and may be regarded as an improvement over the disclosure made in my copending application Serial No. 434,512, filed March 13, 1942, now Patent No. 2,368,469.

An object of the present invention is to provide a simplified, inexpensive generator for oil heaters, such as smudge pots, comprising essentially a U-shaped conduit adapted to be positioned in the oil of the heater with one end of the conduit extending downwardly from above the normal oil level and the other end of the conduit extending upwardly above the normal oil level toward the combustion zone, whereby heated gases and vapors will be drawn through the conduit down into the oil to effectively heat it.

Another object of the invention is to provide a generator having the above-mentioned characteristics wherein the conduit is equipped with a mass of refractory material that contributes to the heating of the oil and which functions somewhat in the nature of a wick that will facilitate starting of the heater.

With the foregoing and other objects in view, which will be made manifest in the following detailed description and specifically pointed out in the appended claims, reference is had to the accompanying drawing for an illustrative embodiment of the invention, wherein:

Figure 1 is a top plan view of an oil heater illustrating the combined generator and lighter in applied position therein;

Fig. 2 is a vertical section through the heater, taken substantially upon the line 2—2 upon Fig. 1 in the direction indicated;

Fig. 3 is a sectional view through the combined generator and lighter taken substantially upon the line 3—3 upon Fig. 2 in the direction indicated.

Referring to the accompanying drawing wherein similar reference characters designate similar parts throughout, the heater in which the combined generator and lighter may be used may vary considerably. A conventional type of construction is illustrated however consisting of a base or receptacle 10 adapted to contain an adequate supply of fuel oil 11 which, when the heater is initially filled, rises to the normal level indicated. A cover 12 is positioned thereon having a central throat 13 on which the stack of the heater is normally positioned. In the cover there is an opening for a hinged damper 14 which can be adjusted to regulate the amount of air that is admitted to the interior of the cover over the surface of the oil and thus adjust the rate of burning.

The combined generator and lighter embodying

the present invention comprises a U-shaped conduit which may be formed of conventional pipe sections and fittings, one leg of the conduit being indicated at 15, which extends downwardly from above the normal level of the oil 11. This pipe section is connected such as by an elbow 16 to a horizontally disposed nipple 17 which, in turn, is connected by an elbow 18 to an upstanding pipe section 19 which provides the other leg of the U-shaped conduit. This section is preferably provided with a threaded coupling 20 which detachably connects a nipple or short length of pipe 21 to the pipe 19. Thus, the upwardly extending leg of the U-shaped conduit is somewhat longer than the downwardly extending leg thereof and extends upwardly into the throat 13 of the cover toward the combustion zone.

Within the crotch of the U-shaped conduit there is positioned a mass of porous refractory material 22 which projects upwardly above the normal level of the oil and which is held in position, such as by a clamp or bracket 23. This clamp or bracket may be formed in several manners, but one simplified form of construction is to provide a U-shaped section of scrap iron or the like, and spot weld it or otherwise secure it to the bottom of the nipple 17. The U-shaped conduit and the U-shaped clamp or bracket being arranged at right angles to each other, serve to maintain the combined generator and lighter in the upright position shown and to prevent tipping. The arms of the clamp or bracket 23 may or may not resiliently engage the sides of the porous refractory material 22.

For purposes of simplicity and cheapness the mass of porous refractory material 22 may be a common unglazed building brick although other materials may be substituted therefor if desired.

The overall width of the combined generator and lighter is preferably slightly smaller than the diameter of the throat 13 so that it is possible to insert the device into the heater through the throat without removing the cover 12. When so inserted the upstanding leg of the U-shaped conduit is positioned centrally of the throat and a projecting corner of the brick 22 is positioned so as to be readily accessible through the opening that is covered by the adjustable damper 14.

In lighting the heater a small quantity of gasoline or other highly volatile and readily combustible fluid is poured through the opening normally covered by the damper 14 onto the top of the brick 22. This gasoline is quickly absorbed by the brick due to its porosity. It is then lighted and functions somewhat in the nature of a wick heating

and causing to be ignited vapors of the fuel oil that rise from its surface. When the fuel oil starts to burn the vapors rising from its surface are partially burned beneath the cover 12 and a draft is soon created through the U-shaped conduit so that these partially burning and heated vapors are drawn downwardly through the U-shaped conduit to cause the body of the oil 11 to be effectively heated. Then all of the vapors that are burning beneath the cover 12 are drawn downwardly through the U-shaped conduit. Some of these vapors rise directly through the throat 13. However, a sufficient fraction of the vapors are carried through the oil by the conduit so that the oil is adequately heated thereby to bring about a clean and virtually smokeless combustion.

I find that when a heater is equipped with a combined generator and lighter embodying the present invention that the efficiency of the heater is materially increased. That is, the same amount of heat is given off with a lower consumption of oil. I find also that the construction is advantageous in extinguishing the flame in that if the supply of air admitted through the damper 14 is completely cut off the flame within the heater will normally extinguish itself in approximately one minute. Apparently under these circumstances, the brick functions to localize the flame thereon and as the available oxygen beneath the cover 12 is used up the remaining flame on the brick extinguishes itself.

Inasmuch as the nipple or pipe section 21 leads to and is closely adjacent the major combustion zone, this portion of the conduit is apt to become burned and corroded with continued usage. However, as it is detachably connected by means of the coupling 20, this portion of the conduit can be readily removed and replaced whenever occasion requires.

It is not essential that the cover 12 be equipped with any stack whatsoever and if desired, any preferred form of stack can be used thereon. However, I prefer to mount on the cover a short stack section 24 which is suitably perforated as indicated at 25 and which carries a downwardly extending conical hood 26. Over this short stack section any conventional type of stack indicated at 27 may be mounted if desired. The perforations 25 admit external air to the major combustion zone and the products of combustion ascend through the stack 27 when this is present.

From the above-described construction it will be appreciated that the improved combined generator and lighter is inexpensive and is quite simple in its construction. It may be installed in any conventional type of oil heater, now in general use, and in the course of its installation it is not necessary to remove the cover 12. When employed it greatly facilitates lighting the heater with considerable certainty of operation. One of the major objections to conventional types of heaters is that if gasoline is poured into the receptacle 10 on top of fuel oil therein and is ignited

that after this initial gasoline has been burned the flame tends to go out. With the present construction if the gasoline is poured onto the projecting portion of the brick 22 and is ignited inasmuch as the brick functions somewhat in the nature of a wick, the lighting of the heater and the starting of the burning of the fuel oil is assured in all instances. Furthermore, when it is desired to extinguish the flame this is likewise readily accomplished with certainty by merely shutting off the air supply afforded through the damper 14.

Various changes may be made in the details of construction without departing from the spirit or scope of the invention as defined by the appended claims.

I claim:

1. A combined generator and lighter for oil heaters comprising means providing a U-shaped conduit adapted to be positioned in the oil of the heater so as to extend downwardly from above the normal oil level, and then upwardly above the oil level toward the combustion zone, a U-shaped bracket mounted on said conduit at the crotch thereof, and a porous brick supported in the crotch of the conduit within the bracket.

2. A combined generator and lighter for oil heaters comprising means providing a U-shaped conduit adapted to be positioned in the oil of the heater so as to extend downwardly from above the normal oil level, and then upwardly above the oil level toward the combustion zone, a U-shaped bracket mounted on said conduit at the crotch thereof, and a porous brick supported in the crotch of the conduit within the bracket, said bracket projecting above the normal oil level.

3. A combined generator and lighter for oil heaters comprising means providing a U-shaped conduit adapted to be positioned in the oil of the heater so as to extend downwardly from above the normal oil level and then upwardly above the oil level toward the combustion zone, a U-shaped bracket mounted on said conduit at the crotch thereof, a porous brick supported in the crotch of the conduit within the bracket, said bracket projecting above the normal oil level, and the top of the upwardly extending portion of the conduit being removable and replaceable.

4. A generator for oil heaters and the like comprising means providing a U-shaped conduit the upstanding sides of which are of unequal length and means providing a wick supported on the conduit, the wick and the shorter arm being adapted to extend above the level to which the oil is normally filled in the heater.

5. A generator for oil heaters and the like comprising means providing a U-shaped conduit the sides of which are of unequal length and a porous brick supported on the conduit between said unequal sides, the wick and shorter side being arranged to project upwardly above the level to which the oil is normally filled in the oil heater.

JOHN S. HODGES.
